UNITED STATES PATENT OFFICE

HARRIS A. LAWTON AND ANDREW J. CARMICHAEL, OF NEW HAVEN, CONNECTICUT,
ASSIGNORS TO THE GREIST MANUFACTURING COMPANY, A CORPORATION OF CONNECTICUT

SEWING-MACHINE RUFFLER

Application filed May 23, 1928. Serial No. 280,036.

This invention relates to that class of sewing machine rufflers, generally known as "five-stitch" rufflers, in that they have heretofore usually been constructed to make a ruffle at each stitch of the sewing machine, or at each five, or a greater or lesser number of stitches; and the invention has for its object to provide a ruffler of the class referred to in which the adjustment from one class of work to the other may be readily and easily effected. The invention is adapted for use in a ruffler provided with a single ratchet wheel constructed with deep and shallow notches, by which the intervals of the strokes of the ruffling blade may be controlled, or with two ratchet wheels mounted on the same pivot pin and constructed with a plurality of deep notches and one of which ratchet wheel is adjustable relative to the other on said pivot pin. In one position occupied by the adjustable ratchet wheel two deep notches on both of said wheels will be in register with each other, so that a ruffling stroke will be imparted to the ruffling blade at each five or six stitches of the machine, according to the number of shallow notches between the deep notches of one of said wheels; while in another position occupied by the adjustable ratchet wheel only a single deep notch of the adjustable wheel will be in register with a deep notch of the other wheel; so that a stroke of the ruffling blade will occur only at each ten or twelve or any other desired number of stitches of the sewing machine. The improved ruffler is also so constructed that, by proper adjustment, a ruffling stroke will be imparted to the ruffling blade at each stitch of the sewing machine; or the ruffling blade may be thrown out of action entirely when plain sewing is to be done.

The present invention relates more particularly to the means for operating the ratchet wheels by the use of two pawls, one of which is fixed relative to a pawl carrier, and the other of which is adjustable on said carrier, so that said adjustable pawl may be readily thrown out of operation when the ruffling blade is to make a stroke at each stitch of the sewing machine.

In the accompanying drawing Figs. 1 and

2 are opposite side views of a ruffler embodying the present invention. Fig. 3 is a plan view of the same; Fig. 4 is a detail view of the pawls and some adjacent parts, and Figs. 5, 6 and 7 are detail views of the ratchet wheels.

Referring to the drawing, 12 denotes the frame of the ruffler provided, as usual, with a forked forward end 13, to adapt the same for attachment to the presser bar of a sewing machine. Mounted on the frame 12, by a pin or rivet 14, is the main operating lever 15 forked at its forward end for engagement with a pin or screw carried by the needle bar of a sewing machine; and, fulcrumed on the pin or rivet 14, is a pendulous lever 16 jointed at its lower end to the ruffling blade carrier 17 to which latter is attached the ruffling blade 17^a. The pendulous lever 16 is provided with an arm 16^a positioned beneath a contact screw 18 carried by the operating lever 15, said screw being frictionally retained in any desired position of adjustment by a spring 19 mounted on said operating lever 15.

Mounted on the pin 14 are two ratchet wheels 23 and 24, adjacent or contiguous to each other. The outer ratchet wheel 23 is provided with three deep notches 23^a and 23^b, the periphery of said wheel being shown as plain between said notches. The ratchet wheel 24 is provided with two deep notches 24^a and with a plurality of shallow notches 24^b between each of said deep notches. In the construction shown there are five of these shallow notches between said deep notches, thus providing for a stroke of the ruffling blade at each six stitches of the sewing machine, although it will be understood that said ratchet wheel might be constructed with a greater or lesser number of these shallow notches between each of the deep notches 24^a.

The ratchet wheels 23 and 24 may be held in frictional engagement with each other, so that they will rotate together. It is preferred, however, to provide the ratchet wheel 23 with an indented lug 23^c which, in one adjustment of said ratchet wheel, will enter a hole or recess 24^c in the ratchet wheel 24, and in another adjustment of the ratchet wheel 23 will

enter the inner part of a deep notch 24^a of the ratchet wheel 24, so as to hold the ratchet wheel 23 in either of these positions of adjustment. The ratchet wheel 23 is provided with an outwardly extending pin or pins 21 for convenience in adjusting said wheel circularly relative to the ratchet wheel 24.

This feature of the two ratchet wheels containing deep and shallow notches, and one of which is circularly adjustable relative to the other is, however, not herein claimed broadly, as this feature is described and claimed in the application of Hugo Maashoff and George W. Pratt, filed May 7, 1928, Serial No. 275,714.

15 The pendulous lever 16 is provided with a shoulder 16^b adapted to be engaged by a pawl 26 integral with a spring-pressed pawl-carrier 27 mounted on the main operating lever 15 and arranged to engage the shoulder 16^b on the pendulous lever 16 when desired.

20 The pawl carrier 27 is provided with lugs 27^a in which is rotatively mounted a bar 28 having at its forward end an integral pawl 29, said bar being square or of polygonal 25 form in cross section so that a spring finger 29^a, bearing against a flat part of said bar, will hold said partially rotatable bar in different positions to which it may be turned. The spring finger is preferably an extension 30 of the usual torsional spring by which the pawl carrier 27 is yieldingly pressed towards the ratchet wheels. The bar 28 is provided with a milled head 30 by which it may be readily turned from the position shown in 35 Fig. 1 to the position shown in Figs. 3 and 4, or vice versa.

30 The pawl bar 28 is rotatively mounted in an approximately horizontal axis in the lugs 27^a of the pawl-carrier 27, so that in its operative position the pawl 29 on said pawl bar is approximately horizontal, as shown in Fig. 1; but when said bar is given a quarter turn said pawl 29 will be in a vertical position, as shown in Figs. 3 and 4, and will be out of register laterally with the ratchet wheels and will thus be inoperative.

40 When the ratchet wheel 23 is in the position of adjustment shown in Fig. 1 the deep notches 23^a of said ratchet wheel will be in register with the two deep notches 24^a of the ratchet wheel 24; and thus, with the ratchet wheels constructed as herein shown, the said pawl 29 will fall into said deep notches 23^a and 24^a, and will thus permit the pawl 26 to engage the said shoulder 16^b on the pendulous lever 16 at each six stitches of the sewing machine, so as to operate the said pendulous lever and impart a forward movement to the ruffling blade carrier and the ruffling blade affixed thereto, the said pawl 26 being held out of engagement with the said shoulder 16^b at other times. This is due to the fact that, excepting when the pawl 29 is in its inoperative position or is in the deep notches of the ratchet wheels, the spring-pressed pawl car-

rier 27, is held back by the engagement of the pawl 29 with the ratchet wheels. When, however, the ratchet wheel 23 is in a position of adjustment to bring the deep notch 23^b in said ratchet wheel into register with one of the deep notches 24^a of the ratchet wheel 24, the other deep notch 24^a of the ratchet wheel 24 will be covered by the ratchet wheel 23, and thus the pawl 29 will, in the rotation of the said ratchet wheels, fall into the said registering deep notches 23^b and 24^a to enable the pawl 26 to impart a forward stroke to the ruffling blade, at each twelve stitches; said pawl being held out of said engagement with the said shoulder 16^b during the formation of eleven stitches.

45 When a ruffle is to be made at each stitch of the sewing machine the adjustable pawl 29 will be turned to the position shown in Figs. 3 and 4, thus throwing it out of operation and permitting the fixed pawl 26 to engage the shoulder 16^b on the pendulous lever 16. When, however, the ruffler is to be thrown out of operation, for plain sewing, the pawl carrier 27 will be withdrawn to the position shown in dotted lines in Fig. 1 and in which position it will be yieldingly retained by an extension 19^a of the spring 19, said extension 50 engaging a recess in said pawl carrier.

55 The ruffler is provided with the usual separator plate 31 affixed to a carrier 32 which is removably attached to the frame 12 in a well-known manner.

60 From the foregoing it will be understood that the invention provides simple means whereby a ruffler is adapted to make a ruffling stroke at each stitch of a sewing machine, or between any desired number of a plurality of stitches, or may be thrown out of operation altogether when plain sewing 100 is to be done.

65 Having thus described our invention we claim and desire to secure by Letters Patent:

1. In a sewing machine ruffler, the combination with an operating lever, a pendulous lever having a shoulder, and a ruffling blade operatively connected with said pendulous lever, of a ratchet wheel having deep and shallow notches, a pawl-carrier pivotally mounted on said operating lever, a pawl fixed relative to said pawl-carrier, and an adjustable pawl carried by a pawl-bar rotatively mounted on said pawl-carrier, so that by giving said bar a quarter turn said pawl will be out of register, laterally, with said ratchet wheel.

70 2. In a sewing machine ruffler, the combination with an operating lever, a pendulous lever having a shoulder, and a ruffling blade operatively connected with said pendulous lever, of a ratchet wheel having deep and shallow notches, a pawl-carrier pivotally mounted on said operating lever, and fixed and adjustable pawls mounted on said pawl-carrier, said pawl-carrier having lugs, a bar 115

rotatably mounted in said lugs and relative to which bar said adjustable pawl is fixed, and means for holding said bar in different positions of adjustment.

5 In testimony whereof we affix our signatures.

HARRIS A. LAWTON.
ANDREW J. CARMICHAEL.
